UNITED STATES PATENT OFFICE.

HOSFORD D. KELLOGG, OF HAVERFORD, PENNSYLVANIA, ASSIGNOR TO KELLOGG RADIATOR COMPANY, A CORPORATION OF DELAWARE.

DESIGN FOR A RADIATOR.

Application filed July 20, 1922. Serial No. 3,140. Term of patent 14 years.

To all whom it may concern:

Be it known that I, HOSFORD D. KELLOGG, a citizen of the United States, and a resident of Haverford, county of Delaware, and State of Pennsylvania, have invented a certain new, original, and ornamental Design for Radiators, as shown in the accompanying drawings in which the figure is a perspective view of a radiator embodying

the new design and as viewed from in front of the same.

I claim:

The ornamental design for a radiator substantially as shown.

In witness whereof, I have hereunto set my hand this twentieth day of July 1922

A. D.

HOSFORD D. KELLOGG.
